UNITED STATES PATENT OFFICE.

JOHN C. SPRAGGINS, OF NEW ORLEANS, LOUISIANA.

TRANSFERABLE SHOW-CASE.

SPECIFICATION forming part of Letters Patent No. 603,210, dated April 26, 1898.

Application filed September 17, 1897. Serial No. 652,047. (No model.)

To all whom it may concern:

Be it known that I, JOHN C. SPRAGGINS, a citizen of the United States, residing at New Orleans, in the parish of Orleans and State of Louisiana, have invented certain new and useful Improvements in Transferable Show-Cases; and I do hereby declare the following to be a full, clear, and exact description of the invention, such as will enable others skilled in the art to which it appertains to make and use the same.

This invention relates to transferable show-cases, and has for its object to provide a simple and efficient mechanical arrangement designed to facilitate the moving of show-cases into a store or their ready removal therefrom, as in the event of fire.

To the accomplishment of this object the invention consists in providing an inclined way extending, for instance, lengthwise of the store and provided with a pair of tracks for the reception of rollers carried upon the bottoms of the cases, which latter are provided with horizontal rollers above their upper edges designed to move along a suitable rod or track, the several cases being retained by a rotary stop, which may be quickly turned out of the path of the cases to permit their ready removal from the frame in which they are held.

Referring to the drawings, Figure 1 is a side elevation of my device complete. Fig. 2 is an end elevation thereof. Fig. 3 is a bottom plan view of one of the cases, and Fig. 4 is a detail perspective view of the stop.

Referring to the numerals on the drawings, 1 and 2 indicate a pair of longitudinally-inclined tracks supported upon suitable standards 3 and designed to receive peripherally-grooved rollers 4, suitably mounted adjacent to the corners of the bottom 5 of a show-case 6 of any suitable design, from the top of which extends a vertical shaft 7, carrying a horizontally-grooved roller 8.

9 indicates a shaft or track extending longitudinally above the show case or cases, as the case may be, and against which the rollers 8 are designed to bear to prevent forward tilting of the show-cases. A series of cases 50 provided with the casters 4 and rollers 8 are

slid upon the inclined way formed by the tracks 1 and 2 and are retained against rolling by gravity down the inclined way by a rotary stop 10, consisting of a semicircular plate 11, carried by a rotary shaft 12, journaled in suitable bearings 13 and secured to the semicircular plate 11 at the center of its straight edge. The shaft, which is disposed horizontally, and the bearings 13, in which it is mounted, are preferably located in the rear 55 of the cases to permit the semicircular plate to lie against the side of the end case or to be turned back out of the path of the cases to permit their rolling by gravity down the inclined plane and their removal with their contents, if desired.

It is evident that in the event of fire the stop may be turned back and that the cases will readily move toward the front end of the store and may be entirely removed with despatch, or that if it is desired to remove any one of the cases it may be readily accomplished in the same manner; but while the present embodiment of my invention appears at this time to be preferable I do not desire to limit 75 myself to the details of construction herein shown and described. I reserve the right to change, modify, or vary them at will within the scope of my invention.

What I claim is—

1. In a device of the character described, the combination with an inclined track, of a show-case carried thereby, and a rotary stop adapted to engage said case for limiting the movement thereof having a segmental engaging portion.

2. In a device of the character described, the combination with an inclined track, of a show-case carrying rollers upon the bottom thereof, designed to be supported by the track, 90 and a stop adapted to engage said case and limit the movement thereof, the said stop consisting of a rotary shaft and a semicircular plate carried thereby.

3. In a device of the character described, 95 the combination with a pair of inclined tracks, of a series of show-cases, casters upon the bottoms of the show-cases designed to be supported by the tracks, horizontal rollers carried at the upper ends of the cases, a track in con- 100

tact with the horizontal rollers, a rotary stop consisting of a horizontal shaft mounted adjacent to the rear edges of the show-cases, and a semicircular plate secured to the shaft 5 at the center of its straight edge, substantially as specified.

In testimony whereof I have signed this

specification in the presence of two subscribing witnesses.

JOHN C. SPRAGGINS.

Witnesses:

JOHN GROTE,
A. W. SOCOLA.
